Primary Examiner — Deanna L Pratt*Assistant Examiner* — Natasha Vujcic(74) *Attorney, Agent, or Firm* — Mark Terry(57) **CLAIM**

The ornamental design for a glass panel bracket and housing for an LED based lighting apparatus, as shown and described.

DESCRIPTION

FIG. 1 is a top perspective view of a glass panel bracket and housing for an LED based lighting apparatus, showing the new design;

FIG. 2 is a bottom perspective view thereof;

FIG. 3 is a front view thereof;

FIG. 4 is a side view thereof;

FIG. 5 is a top view thereof; and,

FIG. 6 is a bottom view thereof.

The broken lines in the drawings illustrate portions of the glass panel bracket and housing for LED based lighting apparatus which form no part of the claimed design.
